ABSTRACT

A flat strip of rigid material is transversely divided into a handle portion and a double-edged working portion. The handle portion is tapered to a free end for additional use as a hair divider. The double-edged working portion is longitudinally divided into combing and cutting edges transversely reduced from a thicker middle section. Comb teeth are defined in one of said double-edges and in the other a longitudinal recess terminates transversely in angular serrations that are spaced longitudinally apart the width of a serration. A blade holder, with a blade slidably mounted therein, is fixed in said recess with the blade guarded by the serrations. A longitudinally operable push-button is mounted near an inboard end of the blade holder in a slot longitudinally aligned therewith and, in extension thereof, positions the blade in the blade holder with respect to the angular serrations to sequentially expose blade portions originally behind the serrations.

2 Claims, 4 Drawing Figures

PATENTED APR 23 1974

3,805,381

HAIR STYLING DEVICE

The invention relates generally to hair styling devices and more particularly to a manual razor hair cutting device.

It is old in the art to style hair with a razor and a comb.

It is an object of the invention to provide a single manually operable device for styling hair.

Another object of the invention is to provide means for razor cutting hair that doubles the life of a guarded cutting blade.

Other objects and a more complete understanding of the invention may be had by referring to the following description, claims and drawings, in which:

FIG. 1 is a perspective view of the invention from above and to one side end,

FIG. 2 is an enlarged perspective exploded view of movable parts of the invention,

FIG. 3 is an enlarged view of a blade usable with the invention, and

FIG. 4 is similar to FIG. 1, showing the invention less moving parts shown in FIGS. 2 and 3.

Referring to FIG. 1, the invention comprises an elongated flat strip of rigid material that is divided transversely into a handle portion 10 and a double-edged working portion 11.

In the double-edged working portion 11, one of the double-edges defined a comb 12, and the other a longitudinal recess 13 (see FIG. 4) with angular serrations 14. The handle portion 10 tapers to a hair-dividing sharp end 16. At the juxtaposition of handle portion 10 and working portion 11, a push button 18 is slidably mounted in a slot 19 defined therein adjacent to a thumb recess 20.

Referring additionally to FIGS. 2 and 3, a blade 22 is adapted to slidably engage in a track 26 and a blade holder 24 which is fixed in recess 13 by means of a threaded bolt 25 at the outboard end of said blade holder. In the middle, retaining track 26 engages blade 22 in the blade holder for a portion of its length. Track 26 is prevented from escaping from the blade holder 24 by a stop 34 at one end of said blade holder and stop 38 adjacent the other end. The square profile of the track holds the blade firmly therein, the track itself being springingly engaged by blade holder 24.

Push button 18 defines a shoulder 28 in a longitudinal foot 30, and end of which engages an inboard end of track 26 in passing over an extended lip 32 of blade holder 24 to hold that end of the blade holder in recess 13. Shoulder 28 cooperates with overcut inboard end of the blade holder as a stop in the longitudinal travel

of the push button in ejecting an old blade from the track and blade holder.

Referring to FIGS. 1 and 4, retaining guides 36 and 40 extend transversely horizontal from foot 30 of the push button and engage in parallel grooves 37 and 41 defined in opposite walls of slot 19 to slidably support said push button 18 in slot 19. When a blade 22 is fully inserted into blade holder 24 and track 26, push button 18 is pushed to the inboard end of slot 19, and an arrow 10 44 inscribed on said push button falls opposite a base index mark 46. The outboard ends of blade 22 and blade holder 24, which is recessed into end recess 42, then coincide. Sliding push button outwardly to coincide with a second index mark 48, that is longitudinally spaced from the index mark 44 by the width of a serration, advances the blade to a position flush with an outboard end of working portion 11 in recess 42 and exposes portions of the blade 22 originally positioned behind serrations 14. Further advancing push button 18 until shoulder 28 engages the inboard end of blade holder 24, pushes the outboard end of blade 22 clear of recess 42 and the outboard end of working portion 11 for grasping by the fingers to complete removal therefrom for the insertion of a new blade.

What is claimed is:

1. A hair styling device comprising: a pointed handle for holding the device and for dividing hair; double-edged working means unitarily in alignment with said handle means for styling said hair; comb means defined in one edge of said double-edged working means for combing out said hair; recess means defined in a second edge of said double-edged working means; blade means having a cutting edge and slidably mounted with said cutting edge exposed in said recess means; angular serration means defined in said second edge for guarding the cutting edge of said blade means, said serration means having serrations spaced apart the width of a serration; and push button means slidably mounted in said device and adapted to longitudinally slide said blade in said recess means between two fully engaged positions therein spaced a serration apart, thereby doubling the working life of said blade means by sequentially exposing the cutting edge of said blade means, including the parts originally shielded behind said serration means.

2. A hair styling device as described in claim 1 wherein said two fully engaged positions of said blade means in said recess with respect to said serration means is indicated by coincident markings on said push button means and said double-edged working means.
